UNITED STATES PATENT OFFICE.

LAMAR H. SHOVER, OF MILWAUKEE, WISCONSIN.

DISPLAY JAR STAND.

Application filed December 22, 1924. Serial No. 757,464.

To all whom it may concern:

Be it known that I, LAMAR H. SHOVER, a citizen of the United States, and resident of Milwaukee, in the county of Milwaukee and

5 State of Wisconsin, have invented certain new and useful Improvements in Display Jar Stands; and I do hereby declare that the following is a full, clear, and exact description thereof.

10 This invention relates to display jar stands.

Objects of this invention are to provide a display jar stand in which a plurality of jars are removably mounted and are adapted 15 to revolve about a central axis so as to display any desired jar in an attractive and simple manner, to provide a display stand in which the jars are securely locked in position, and to provide means to permit the 20 ready tipping or rocking of the jars and to thereafter hold such jars in a slanting position to facilitate removing of the contents such as candy thereof during dispensing.

It is to be noted that patrons may rock 25 the jars around in a free manner and it therefore is necessary to provide means for preventing inadvertent tipping of the jars without the sanction of the dispenser.

A further object is to provide means for 30 permitting tipping of the jars at only one position with reference to the supporting stand. For example, the store keeper may so set the display stand that the jars may be tipped only when they are presented towards 35 him and are remote from the customer.

Further objects are to provide a jar display stand which will take any of the usual 40 types of display jars and securely hold them against upsetting or falling from the stand and which is provided with means whereby the jars rock approximately about their centers of gravity when moved to dispensing 45 position and are locked in either their vertical or their angular dispensing position in a simple and easy manner.

Further objects are to provide a simple, cheap and attractive form of display stand which may be readily manufactured by ordinary machine shop methods.

50 An embodiment of the invention is shown in the accompanying drawings, in which:—

Figure 1 is a partial vertical sectional view through the device showing two of the jars in dotted lines.

Figure 2 is a plan view of the structure 55 shown in Figure 1 with one of the jars shown in position and with one of the supporting structures in section.

Figure 3 is a fragmentary sectional detail 60 of one of the latching means for the jars.

The display stand comprises a supporting base 1 which may be of any suitable size and attractive design. This supporting base is provided with a threaded aperture into which the threaded reduced extension 2 of a 65 short stub shaft or supporting spindle is secured. This spindle is provided with a shoulder or collar 4 adjacent its lower end which clamps tightly against the top of the base and also provides shoulders upon which 70 the hub of the revolving portion rests, as will be described later. The upper portion of the spindle is also reduced and threaded, as indicated at 5, and receives a plate 6. Preferably the aperture in the plate 6 as well 75 as the lower portion 7 of the reduced upper portion of the spindle 3 are square to prevent rotation of the plate 6 with reference to the spindle 3. A clamping nut 8 is 80 screwed upon the reducing portion 5 and clamps the plate in position. The spindle 3 is apertured and receives the reduced end 9 of an upright standard 10, such standard being adapted to carry any suitable decorative or advertising means, or in fact an additional jar at its upper end in a well known manner, the upper portion of the standard 85 being omitted for the sake of clearness.

The revoluble portion of the display stand comprises a pair of disks 11 between which 90 are riveted the inner ends of the downwardly curved outwardly projecting supporting channel arms 12, as clearly shown in Figure 1. These channel arms carry the transverse or base portion 13 of U-shaped 95 supporting members provided with upstanding arms 14. The upstanding arms of the U-shaped members pivotally carry jar receiving straps 15.

It is to be noted that a basket-like support 100 is carried by each of the rings or straps 14; for example, one of the supporting members of this basket-like portion is indicated at 16 and comprises a U-shaped member, as illustrated in the drawings. A correspond- 105 ing U-shaped member 17 is positioned at right angles to the member 16 and the upper ends of such members are securely attached

to the ring 15 and such members are further securely attached to each other at their point of crossing.

One of the members 17 carries an arcuate plane 18 provided with an inner and an outer notch 19 and 20. The corresponding upright 14 is provided with a bracket or with a pair of outwardly projecting ears 21 (see Figure 3) between which is pivotally mounted a latching lever 22, such latching lever being provided with a curved outer manipulating end, as shown. The inner end of the latching lever constitutes a locking pawl 23 which projects through an aperture 24 in the upright 14, and which is adapted to enter either of the notches 19 or 20 formed in the corresponding arcuate member 18, as may be seen most clearly from Figure 1. Each of the arcuate members 18 form in effect notched segmental devices and are provided with outwardly turned ears 25 at their ends which contact with the upright 14 and thus limit swinging of the jar carrying frame, as shown in dotted and full lines in the left hand portion of Figure 1.

In using the device, the jaws are positioned in their respective baskets or supporting members and are positioned vertically, the latches 22 rocking into place and holding the jars against tilting. When it is desired to tilt a jar as for instance during dispensing, it is merely necessary to lift the corresponding latch 22 and rock the jar into dotted line position, as shown in Figure 1, the gravity urged latch snapping into the outermost notch 20 when the jar arrives at its outer tilted position. The jar is thus securely held in a tilted position while dispensing takes place. Thereafter, it is merely necessary to release the latch. The jars are rocked back into vertical position for the center or pivot points are slightly above the centers of gravity of the jars.

In order to prevent unauthorized tipping of the jars, the members 16 are provided with fins 26 on their lower sides which have curved bottoms and which have abrupt inner shoulders 27. The shoulders 27 are positioned in proximity to the peripheral edge of the disk 6, engaging such peripheral edge when it is attempted to tilt the jar. However, at some point in the peripheral portion of the disk 6 a notch 28 is formed as shown on the left hand side of Figure 1 and this notch will permit the free sliding or passage therethrough of a fin 26, as shown in dotted lines, when such fin registers with the notch.

It is to be noted that the fins are of sufficient extent to prevent their disengaging from the notch when the corresponding jar is in completely tilted position.

It will be seen, therefore, that the jar cannot be tipped by the customer on his side of the stand and may only be tipped by the dealer at a specific point on the dealer's side of the stand. Further, the device cannot be rotated while a particular jar is in its tipped position, as the frame is then locked rigidly to the base portion.

It will be seen that a highly serviceable and efficient type of jar display stand has been provided in which the several jars may be rotated past the customer until a selection is made and the particular jar from which dispensing is to take place may be rotated to a position in front of the dealer. Thereafter the latch may be released and the jar rocked towards the dealer.

It is to be seen also that tampering with the device by customers is prevented and unauthorized tipping of the jar is wholly avoided.

It will also be seen that a compact, attractive and strong display stand has been provided which may be cheaply and readily made.

Although the invention has been described in considerable detail, it is to be understood that the invention may be variously embodied and is, therefore, to be limited only as claimed.

I claim:

A display stand for jars comprising a base, a revoluble member carried thereby, a plurality of upwardly extending spaced arms secured to said revoluble member, jar receiving baskets pivoted between said arms, latches for locking said baskets in vertical or tilting positions, a fin carried by the lower end of each of said baskets, and a circular plate rigidly locked with reference to said base and having its peripheral portion in proximity to said fins to prevent unauthorized tilting of said baskets, said plate having a notch through one portion of its periphery adapted to receive a fin and permit tilting of a basket when said basket occupies a predetermined position.

In testimony that I claim the foregoing I have hereunto set my hand at Milwaukee, in the county of Milwaukee and State of Wisconsin.

LAMAR H. SHOVER.
